UNITED STATES PATENT OFFICE.

GEORGE R. WEST, OF PITTSBURGH, PENNSYLVANIA.

COMMODITY CONTAINER.

1,210,121.

Specification of Letters Patent. Patented Dec. 26, 1916.

Application filed June 25, 1915. Serial No. 36,350.

To all whom it may concern:

Be it known that I, George R. West, a citizen of the United States, residing at Pittsburgh, county of Allegheny and State of Pennsylvania, have invented certain new and useful Improvements in Commodity Containers, of which the following is a specification.

The present invention relates to improvements in wheeled commodity containers, and more particularly to structures adapted to form a wheeled toy when the commodity has been removed.

Commodity containers which are adapted for vending purposes in which the container forms a part of the vended package and which provide an attractive display of the contents have been employed in various forms, some of which have been replicas of various articles in commercial use, such as telephones, etc., these devices being adapted to contain the commodity such as candy in pellet form, the container, after the contents have been removed, forming an ornament. In view of the manner in which this type of container is vended, the construction and contents of the container must be such as to enable the invention to be produced at very low cost of manufacture.

Heretofore, these devices have generally been ornamental in appearance, but of substantially no value as a toy, the limits relative to cost of manufacture being such as to prevent an intricate or elaborate construction, especially as it is desirable that the container be of a form which will not damage the commodity, the material employed generally being glass or other vitreous material, pressed glass not only proving attractive in appearance and durable in construction, but also enabling the commodity to be seen through the container walls. In the present invention, I have provided a container for this purpose which is not only ornamental but is usable as a toy, the construction being in the form of a wheeled structure which is not only attractive in appearance, but serviceable when employed as a toy, and yet capable of being manufactured at very low cost. In producing this result, I have found that by the relative arrangement of parts and the particular manner in which they are formed, I am able to produce a toy which, within its particular range of action, is far superior to the usual type of toys operating in this

manner, the toy of the present invention giving the effect of a toy of relatively high cost of manufacture. For instance, the toy of the present invention will operate similarly to a wheeled toy mounted on roller bearings, this being due to the particular construction and arrangement of parts.

The objects of the invention are therefore to provide a construction of this type which is neat and attractive in appearance, durable in construction, efficient in operation, and which can be manufactured at a low cost.

To these and other ends, my invention consists in the improved construction and combination of parts hereinafter fully described, illustrated in the accompanying drawings, and particularly pointed out in the appended claims.

In the accompanying drawing, in which similar reference characters indicate similar parts in each of the views, Figure 1 is a side elevation of a container of this type in the form of a toy embodying the principles of the present invention. Fig. 2 is a vertical longitudinal sectional view of the same. Fig. 3 is a vertical cross sectional view taken on the line 3—3 of Fig. 2. Fig. 4 is a detail sectional view of one of the wheel structures.

The commodity container in the present disclosure of the invention is shown as the chassis and body of an automobile of the limousine type, the container being formed of glass pressed into shape, the portion within which the commodity is received being indicated at 11, the container being indicated generally at 10, the part 11 being shown as having an open top, normally closed by a slide 12 having opposite edges extending into grooves formed in the body portion of the container. The slide, in this instance, is of a length greater than the length of the opening, and normally projects over a depressed portion of the container indicated at 13, to simulate a top extending over the driver's seat. The front portion of the container is shown in the form of the usual hood and radiator structure of an automobile, this being indicated at 14. The container also has a suitable rib-like structure indicated at 15 which may represent the step and mud guards of the automobile, these parts, with the exception of the slide 12, being pressed into shape, and of an integral structure. This form of

chassis and body is mainly an example, it being readily understood that various other forms may be given thereto to meet the individual desires of the trade.

5 A characteristic feature of this construction of container is the employment of depending lugs 16 at the front and back, the container being of a form in which both front and rear supporting wheels are employed. Obviously, where the container is 10 of a different form, as where it simulates a go-cart, but one pair of lugs would be provided. These lugs are arranged in pairs, one pair being at the front and provided 15 with alined openings 17, the other pair being at the rear and having alined openings 17^a. These lugs are formed integral with the chassis structure, being of glass or other vitreous material, the distance between the 20 outer faces of a pair of the lugs being the same in order that the wheel structure may be used interchangeably at the front and at the back.

A wheel structure practically comprises a 25 pair of wheels stamped out of sheet metal, mounted on an axle, the general arrangement being shown in Fig. 3, and an enlarged showing in Fig. 4. As shown, the axle 18 is formed with reduced ends over 30 which the wheels are passed and riveted, thereby making the axle and wheels a unitary structure. These parts are formed of metal and by reason of the riveting action, are arranged free from relative movement, 35 so that when a wheel structure is placed in position, all movements thereof are as a unit, and since the bearings within which the structure is mounted are of glass or vitreous material, it will be understood that 40 friction within the bearings is reduced to a negligible quantity even though each lug is of a thickness which will give an extended bearing surface contact between the lug and axle. The apertured lugs are not only of 45 sufficient strength to prevent bending or breaking, but provide an operating effect equal to that which would be provided by the use of roller bearings. In addition, the axle is of a form and strength to provide 50 against bending, so that the toy will remain serviceable even though subjected to rough usage. In this connection, the wheels indicated at 19, although of sheet form, 55 are given a strength by the crimped portions indicated at 19^a and 19^b, the latter forming a depression within which the riveted end of the axle extends, and at the same time providing a reduced surface

which may pass into contact with the outer face of the lugs in use without material 60 friction being produced.

The wheel structure is applied by first riveting one wheel to the axle and then passing the axle through the alined openings 17 or 17^a, and then riveting the other wheel 65 in position on the axle.

As will be readily understood, this construction of wheel structure can be produced at an exceedingly small cost, while the chassis or body portion including the lugs 70 can also be produced at a low cost, the whole forming not only a novelty as to appearance, but a structure which is usable as a serviceable toy, capable of withstanding rough usage while possessing the efficiency 75 in operation possessed by toys of greatly increased cost of manufacture.

What I claim is:—

1. A combined commodity container and wheeled toy comprising a glass body having 80 a commodity-receiving chamber, axles extending through and loosely mounted in said body, and wheels carried by the axles.

2. A combined commodity container and wheeled toy comprising a glass body having 85 a commodity receiving chamber and having integral depending lugs each having a lateral opening, said lugs being arranged in pairs with the openings in alinement, and a wheeled axle loosely mounted in and extending through each pair of lugs, the axle and its wheels being formed to rotate in unison, whereby the walls of said openings will form bearings within which the axles 95 are free to rotate.

3. A wheeled commodity container comprising a glass body portion and having a commodity receiving chamber, said body portion having integral depending lugs arranged in pairs, each pair having alined 100 openings, and a wheel unit carried by each pair of lugs with the axle extending through the alined openings, said wheel structure embodying an axle having reduced ends, a wheel mounted on each reduced end with 105 the end of the axle riveted on the outer side of the wheel to firmly unite the axle and wheel to provide wheel and axle movements in unison, said axles being loosely mounted in and free to rotate within said lugs. 110

In testimony whereof I affix my signature in presence of two witnesses.

GEORGE R. WEST.
